US00D786840S

(12) **United States Design Patent** (10) **Patent No.:** **US D786,840 S**
He et al. (45) **Date of Patent:** **** May 16, 2017**

(54) **ANTENNA**

(71) Applicant: **Airgain Incorporated**, San Diego, CA (US)

(72) Inventors: **Ziming He**, Irvine, CA (US); **Simon Yang**, Carlsbad, CA (US)

(73) Assignee: **Airgain Incorporated**, San Diego, CA (US)

(**) Term: **15 Years**

(21) Appl. No.: **29/555,958**

(22) Filed: **Feb. 25, 2016**

(51) LOC (10) Cl. **14-03**
(52) U.S. Cl. **USPC D14/230**

(58) **Field of Classification Search**

USPC D14/138, 230-238.1, 299, 358; D13/182
CPC H01L 33/48; H01L 33/02;
H05K 5/00; H01Q 13/10

See application file for complete search history.

(74) Attorney, Agent, or Firm — Clause Eight IPS;
Michael Catania

(57) **CLAIM**

The ornamental design for an antenna, as shown and described.

DESCRIPTION

FIG. 1 is a top perspective view of the first embodiment of an antenna, showing our new design;
FIG. 2 is a top plan view thereof;
FIG. 3 is a front elevation view thereof;
FIG. 4 is a bottom plan view thereof;
FIG. 5 is a side elevation view thereof;
FIG. 6 is a top perspective view of the second embodiment of an antenna;
FIG. 7 is a top plan view thereof;
FIG. 8 is a front elevation view thereof;
FIG. 9 is a bottom plan view thereof;
FIG. 10 is a side elevation view thereof;
FIG. 11 is a top perspective view of the third embodiment of an antenna;
FIG. 12 is a top plan view thereof;
FIG. 13 is a front elevation view thereof;
FIG. 14 is a bottom plan view thereof;
FIG. 15 is a side elevation view thereof;
FIG. 16 is a top perspective view of the fourth embodiment of an antenna;
FIG. 17 is a top plan view thereof;
FIG. 18 is a front elevation view thereof;
FIG. 19 is a bottom plan view thereof; and,
FIG. 20 is a side elevation view thereof.
